UNITED STATES PATENT OFFICE.

JOHN H. HOLTON, OF NORRISTOWN, PENNSYLVANIA.

PROCESS FOR AND APPARATUS FOR THE TREATMENT WITH FLUIDS OF YARNS IN CHAIN WARP AND ANALOGOUS FORM.

Application filed May 29, 1926, Serial No. 112,544, and in Great Britain January 1, 1926.

In the manufacture of textile fabrics the Brandwoods have introduced into use the improvements shown in their Patent No. 1,174,662, dated March 17, 1916, and other 5 patents by which the yarn is wound in single threads on a beam and dyed while thereon. This process and apparatus results in a great saving in two ways: first, the Brandwood process of dyeing is in itself materially 10 cheaper than the prior art, and, second, it is an advantage to have the threads separate, as thus the expense of combining the single threads into ropes, called chains, and then separating them for the subsequent processes, 15 is avoided.

The usual Brandwood apparatus cannot, however, always be profitably employed, as the number of threads to be dyed is insufficient to fill the machine, and in such cases it has 20 been usual to dye the yarn in ropes or "chains" in accordance with the processes prior to the Brandwood invention at a greatly increased expense.

I have conceived the idea of arranging the 25 yarn in such cases in a chain and winding it on the patented Brandwood dyeing beam, and dyeing it in the Brandwood method, thus making the saving incident to the Brandwood dyeing process with the loss only of the expense of combining the yarn into chains and 30 again separating it. I have found that this is a great saving over dyeing by the art prior to Brandwood.

In dyeing by the Brandwood method of 35 forcing the dyes outward from the shaft upon which the yarn is wound and then from the outside inward through the yarn and the shaft upon which it is wound, it is of the utmost importance that the yarn be evenly 40 spaced and uniformly wound and wound close to the flanges of the beam, as otherwise the dye will pass through the path of least resistance, thus one portion of the yarn will be more strongly dyed than other portions. 45 This is comparatively simple to arrange when the yarns are wound singly, according to the Brandwood method, but presents much difficulty when applied to dyeing a chain of 50 yarn upon a beam by a method designed for dyeing single threads.

I have, however, invented an apparatus by which the chain can be uniformly laid upon the beam in such a manner that the entire 55 chain of threads will be dyed upon the Brand-

wood machine to which my improvement has 55 been applied, and will if sufficient care is used be dyed as evenly for all practical purposes as when dyed in single threads according to the Brandwood patents, thus making the Brandwood beam dyeing process applicable to chain dyeing. 60

The process, with my practical apparatus for winding the warps upon a beam for the purpose stated, will now be fully described, reference being had to the drawings where- 65 in—

Figure 1 is a side elevation of the apparatus for winding the warps upon a beam;

Figure 2 is a plan of Figure 1;

Figure 3 is a detail plan to an enlarged 70 scale of the pivot for the traversing arm;

Figures 4 and 5 are two detail views to an enlarged scale of the means for traversing the traverse arm across the apparatus;

Figure 6 is a detail plan to an enlarged 75 scale of part of the traverse arm showing the arrangement of the slot to receive the traversing half nut member;

Figures 7 and 8 show side elevations of a 80 modified tension device.

Referring to the drawings, the frame of the apparatus consists of a post 6 of truncated pyramidal form—hereinafter referred to as the fulcrum post—, the central frame composed of posts 7 and 8 supporting the flat 85 top 9, these posts being referred to herein- after as the central frame posts, and the posts 10 and 11 connected by the round section bar 12 which engages therewith through lugs 13 and is secured by nuts. These latter posts 90 will be hereinafter referred to when necessary as the beaming frame.

On each post 10 and 11 of the beaming frame is pivoted a cranked arm 14 by means of a stud or spindle 15 on which fits a bush or sleeve formed solid with such arm. Each arm 14 is formed at its outer end with a cranked portion to serve for the reception of the neck of a shaft 16, which is passed through a beam 17 and which necks are secured 95 against lifting by the latch 18 which is pivoted at 19 as shown in Figures 1 and 2, and securable in its latched position by any suitable means. A curved handle 20 on each arm 14 serves as manipulating means for the said arm when required. A friction driving drum 21 is borne on a shaft 22 rotatable in the pedestal bearings 23 bolted on a project- 100 105

ing ledge of each post 10 and 11 of the beam-ing frame, and rotatable by means of a pul-ley 24, Figure 2, from a convenient line shaft so that the beam 17 may be rotated by its friction with the said drum. This method of mounting and rotating a beam differs in no essential detail from the known method employed in beam warpers for single ends of yarn.

Upon the beam shaft 16 is pinned or keyed the chain wheel 25 which by a chain 26 com-municates its motion to a chain wheel 27 com-pounded with a chain pinion 28, the latter driving by chain 29 the sprocket 30. The sprocket 30 is keyed on the neck of screw shaft 31, which neck passes through a pedestal bearing 32 bolted to the flat top 9 of the central frame, as shown in Figure 2. The shaft 31 itself is borne in the bearings 33 and 34, bolted to the central frame top 9, and each bearing 33 and 34 is formed double to receive also the shaft 35, which is parallel to the screw shaft 31. The latter is formed on its central portion with a double screw 36 in which en-gages the half nut 37—see detail Figure 5—fitted in the pendent member 38. The latter is formed integral with a boss 39 which is slidable upon the guide shaft 35. A curved plate 40 is secured to a lug 41, integral with the boss 39, such plate 40 sliding upon the op-posite side of the screw shaft 31 to that in which the half nut 37 engages. Secured in the boss 39 is the vertical pin 42 which en-gages in a slot 43 formed in a traverse arm 44. Secured in one end of the slot 43, in the wooden traverse arm 44, by means of a bolt 45, are two thin metal plates 46 which pass on each side of the vertical pin 42 and are se-cured together at their free ends. These plates 46 prevent the vertical pin 42 from wearing away the sides of the wooden slot 43. Two adjusting screws 47 are also provided near the free ends of the plates to adjust said plates and consequently the traverse arm 44 sidewise.

The traverse arm 44, which may be of wood, and which is fulcrumed on a vertical arm 48 of a bracket 49, the horizontal mem-ber of which is adapted to slide upon the top of the fulcrum post 6 and is adjustably se-cured thereon by the bolt 50 passing through the slot 51 and nut 52. The upper extremity of the vertical arm 48 is turned down in di-ameter and threaded to receive the nut 53 which holds the end of the traverse arm 44 in position whilst allowing it to be angularly moved on the vertical arm 48.

At the free end of the traverse arm 44 is fitted the yarn guide 54 which, in the form shown in the drawings, is a flanged tubular eye fitting partly within the recessed end of the said arm and secured in position by means of the metal band 55.

The method of winding the chain warps in a compact and even mass on the beam will

now be understood. From any suitable source of supply, and under a suitable tension device not shown, the warps α are led down-wardly through the guide 54 to be wound upon the beam 17 below. The driving drum 70 21 being rotated, the beam 17 rotates, together with the beam shaft 16, and the latter through chain wheel 25, chain 26, wheel and pinions 27 and 28, chain 29, and sprocket 30 rotates the screw shaft 31 thus reciprocating the half 75 nut 37 along the double screw 36. The half nut 37 being mounted on the pendent mem-ber 38 as previously described and the pendent member being borne by the traversing arm 44, the arm 44 as the half nut 37 and 80 member 38 reciprocate the double threaded length 36 of the shaft 37 has oscillating motion around its fulcrum point on the vertical arm 48, thus traversing the yarn α along the length of the yarn bearing surface of the 85 beam, until the latter is filled, when it is re-moved for treatment.

The traverse arm 44 is made so long that the difference between the length of arc de-scribed by the traverse arm 44 and the tan-90 gent thereto formed by the shafts 35, 36, is unimportant.

The beam shaft 16, as will be seen, can with its chain wheel 25 be freed from the chain 26 for removal of the beam, the parts being 95 again put in operable position on the placing of an empty beam in the bearing arms 14.

The rate of traverse of the yarn will de-pend upon the ratio of angular speed of the beam shaft 16 and of the screw shaft 31, as 100 controlled by the ratios of the chain gearing. In consequence, there will be the same num-ber of rotations of the beam shaft 16 for each traverse of the arm 44, regardless of the in-crease of the external diameter of the yarn 105 mass as the winding progresses. This ratio should preferably be so arranged that at each turn of the beam 17 the chain wound will slightly overlap the coil laid at the preceding turn. The coils are parallel to each other as 110 in an ordinary spool of cotton, but are ar-ranged to overlap. The yarn is overlapped suffi-ciently to prevent dye stuff from squirting out between the coils radially of the beam, and not so much as to form ridges which 115 would impair the smooth and uniform sur-face of the wound yarn. Inasmuch, however, as the chains may vary in thickness from 300 threads more or less to 600 threads more or less, a change of ratio would be necessary at 120 each change of thickness to prevent either spacing between coils or over-lapping. In fact, however, if the traverse moves at each rotation of the beam shaft 16 to such an ex-tent that the chain lies slightly overlapping 125 the coil laid at the previous rotation of the beam shaft 16 when a chain of minimum size is used, say 300 threads, I find that when a chain is used consisting of 600 threads the coils will nevertheless lie uniformly though 120

in

of course overlapping more, and the dyeing will proceed properly. A ratio must not, however, be used which will result in an uneven wind so that the passage of the dyeing fluid through the mass will be resisted less in 5 one place than in another.

It will be noted that as the warps are wound on by friction of the drum 21, the external diameter of the yarn mass on the beam 10 will gradually increase, thus gradually lessening the angular speed of the chain wheel 25 and consequently of the screw shaft 31, but without changing the ratio of traverse to 15 turns of the beam shaft 16 or the character of the wind.

It is necessary that the traverse carry the 20 yarn the full width of the beam at each end of each traverse. As the chains of yarn being dyed vary materially in thickness, the traverse must vary according to the thickness 25 of the chain or there will be a plane of no resistance or higher resistance for the dye at each end of the beam. I have provided means for changing the traverse without changing 30 the timing of the traverse with relation to the revolutions of the beam consisting of the slot 51 in the bracket 49, by means of which the extent of traverse of the guide 54 may be varied to bring the yarn up to the flanges of the 35 beam 17 at each traverse. It will be seen that as the traverse arm is moved forward by the sliding forward of the slot 51 with relation to the bolt 50, the slot 43 in the traverse arm slides forward upon the pin 42 and the traverse of the guide 54 is increased and the reverse effect is caused by the sliding backwards of the slot.

The plates 46 can be adjusted sidewise by 40 the adjusting screws 47. This permits an accurate sidewise adjustment of the traverse so that it will end equally closely to the opposite sides of the beam.

It is important also that the yarn be wound upon the beam at uniform tension and so regulated that the dye will permeate the interior threads of the chain as readily as the exterior threads, that is, will pass through the chain as readily as between its coils or substantially so. This is best accomplished if the chains are 50 wound under light tension. Any suitable tension device may be used and the dyer may use as much tension as he finds satisfactory. If a light tension is desired, the device shown in Fig. 7 has many advantages.

The yarn from the creel is led through a 55 guide 55 in the traverse arm 44 to the roll 21 around which it passes upward between rolls 17 and 21 to and through a guide 58 attached to arm 44 by a bracket 57 and thence downward to the roll 17. The result of this construction is that the yarn is fed forward firmly at the exact speed needed and at a uniform tension, which is so slight as to be almost imperceptible.

60 The treatment of the beam when wound

will be on the desired lines. Patent No. 1,174,662, before referred to, describes the treatment of a wound beam and further description of the means for forcing fluids through the yarns and through the perforated surface of the beam is therefore considered unnecessary here.

My invention can be used also to dye a chain of yarn by winding it on a beam already wound in part with single threads according 75 to the Brandwood invention and such dyeing is included in my method.

It will be understood that although the foregoing includes a description of a practical apparatus for winding chain and analogous warps upon a perforated beam for fluid treatment of the said warps in mass, I do not consider myself confined to such apparatus exactly as described for the carrying out of the process. The method claims are not 80 limited to the particular apparatus herein disclosed for carrying it out.

The word "uniform" is not used in this specification to mean mathematical uniformity but only sufficient uniformity of a thread in 90 correlation with adjacent threads to secure a commercial uniform permeability of the thread mass to the dyestuffs so that the dyed product will be commercially free from streakiness.

95 I claim:—

1. In apparatus of the character described, the combination, with a winding device having a perforated beam provided with end flanges, of traverse mechanism provided with 100 a pivoted arm having at one end a guide for laying the yarn on the beam, driving mechanism operatively connecting the winding device with the traverse mechanism and driving the latter at a uniform and relatively slow 105 speed and constraining the yarn to wind on the beam in coils the side portion of each of which overlaps the adjacent and preceding coil to a predetermined extent, said traverse mechanism operating also to press the end coils of the yarn against the beam flanges with a predetermined pressure, a stationary support provided with a pivot for the other end of the said arm, and a tension device which 110 delivers the yarn to the beam under a uniform and predetermined light pressure, the said parts operating so that the whole mass of 115 yarn on the beam is uniformly permeable to liquid dye stuff.

120 2. In apparatus of the character described, the combination, with a winding device having a perforated beam provided with end flanges, of traverse mechanism provided with a pivoted arm having a guide at one end for laying the yarn on the beam, said arm being provided with means for changing the length 125 of traverse of the guide so as to cause the end coils of the yarn to bear on the beam flanges with a predetermined pressure, a stationary support provided with a pivot for the 130

other end of the said arm, and driving mechanism operatively connecting the winding device with the traverse mechanism.

3. A combination of parts as set forth in claim 2, the said arm being pivoted to a longitudinally adjustable bracket adjustably secured to the said stationary support, and being actuated at a point between its ends.

4. In apparatus of the character described, the combination, with a winding device having a perforated beam provided with end flanges, of traverse mechanism provided with a pivoted arm having a guide at one end for laying the yarn on the beam, said arm being provided with means for adjusting the traverse of the guide so as to set it more or less towards one or the other of the beam flanges, a stationary support provided with a pivot for the other end of the said arm, and driving mechanism operatively connecting the winding device with the traverse mechanism.

5. A combination of parts as set forth in claim 4, the said means for adjusting the traverse of the guide comprising two plates spaced apart and connected to the said arm

at one end, means for adjusting the free ends of the plates laterally of the arm, and an actuating pin for the arm arranged in the space between the two plates.

6. A method of preparing yarn for dyeing, which consists in winding the yarn upon a perforated beam provided with end flanges, said yarn being wound at a uniform and relatively slow speed at all points of its traverse between the beam flanges, and being wound under a constant and predetermined light tension in coils one side portion of each of which is arranged to overlap one side portion of the adjacent and preceding coil to a predetermined extent, and with the end coils of the yarn bearing against the beam flanges with a predetermined pressure, whereby the whole mass of yarn on the beam is rendered uniformly permeable to liquid dye stuff when forced back and forth through the yarn and perforated beam and the dye stuff is prevented from passing radially between the coils.

In testimony whereof I have hereunto set my hand.

JOHN H. HOLTON.
